UNITED STATES PATENT OFFICE

2,250,279

SUCTION CLEANER

Charles H. Sparklin, Chicago, Ill., assignor to
Birtman Electric Company, Chicago, Ill., a corporation of Illinois

Application May 22, 1939, Serial No. 275,091

3 Claims. (Cl. 15—8)

This invention relates to improvements in suction cleaners and more especially to an automatic brush feed therefor.

The invention relates particularly to the type of cleaner employing a rotating brush. This brush is ordinarily located within the nozzle and, in any event, adjacent to the nozzle. During the operation of the cleaner the bristles slowly wear so that after continued use the brush may be too high above the surface being cleaned unless it is fed or adjusted downwardly sufficiently to compensate for the wear.

Heretofore such downward feeding or adjustment of the brush has been done manually; but it is obvious that in such construction it is likely that necessary adjustments will be neglected or improperly timed or performed. The principal feature of my invention is the provision of automatic means actuated by operation of the cleaner for feeding the brush downwardly at a rate to compensate for the wear of the brush. Since the feed is actuated by operation of the cleaner it will be seen that it will always feed the brush downwardly at a rate commensurate with the rate of wear of the brush.

Another feature of my invention is the provision of means for resetting the brush feed so that upon installation of a new brush the feeding means can be quickly and easily reset to start over again.

Other features and advantages of my invention will appear more fully as I proceed with my specification.

In that form of device embodying the features of my invention shown in the accompanying drawings Fig. 1 is a bottom plan view, Fig. 2 is a view taken as indicated by the line 2 of Fig. 1, Fig. 3 is a vertical sectional view taken transversely through the nozzle, Fig. 4 is a view taken as indicated by the line 4 of Fig. 3, Fig. 5 is a view taken as indicated by the line 5 of Fig. 3, Fig. 6 is a view taken as indicated by the line 6 of Fig. 7, Fig. 7 is a view taken as indicated by the line 7 of Fig. 6, Fig. 8 is a view taken as indicated by the line 8 of Fig. 7, and Fig. 9 is a view taken as indicated by the line 9 of Fig. 6.

In the drawings, the complete suction cleaner is not shown as that is unnecessary to illustrate the present invention. It is to be understood that the invention may be used on any kind of suction cleaner and is particularly adapted for use on the conventional vacuum or suction cleaner embodying a nozzle, suction producing means, and ordinarily a dust collecting bag.

As here shown 10 indicates the nozzle of a suc-

tion cleaner and 11, 11 the lips thereof adapted to be brought into contact with or close to the material being cleaned.

Inside of the nozzle is a conventional rotatable brush 12 with the bristles 13, said brush being rotated in a well known manner by means of the belt 14 driven from suitable means (not shown). The ends of the brush are provided with pivots or trunnions 15 mounted in the bearing blocks 16 mounted in the brush carriers 17. 18 may indicate an adjusting screw in each brush carrier to position the mounting of the bearing blocks 16 therein.

Means are provided for automatically and slowly feeding the brush carriers 17 downwardly to compensate for wear of the bristles. Such feeding means is mounted in the casing 20 here shown as located just back of the nozzle. In the present instance the casing 20 is attached to the fan casing 21 by the screws 22, 22.

23 indicates a reciprocable shoe or drag member adapted to engage frictionally the surface of the material being cleaned. Reciprocations of this member caused by back and forth movement 25 of the cleaner operate through mechanism in the casing 20 slowly to feed the brush downwardly. The brush holder 17 at each end of the nozzle is carried by a plate 17a pivoted at 26. The brush holders 17 are lowered or rocked 30 downwardly on the pivots 26. Since the connection between the brush holder at each end of the nozzle with the feed mechanism is similar, I shall describe but one. 30 indicates a polygonal shaft pivoted in the nozzle walls at 31, 31. This 35 shaft carries a crank 32 at the inner end. 33 indicates an arm mounted on the shaft 30 having a depending extension 34 connected by the screw 35 to the brush carrier 17. It is to be understood that there is a similar arrangement 40 at each end of the nozzle. The rocking of the shafts 30 will therefore lower the brush holders 17. The connection of the extension 34 with the screw 35 is loose enough so that the downward movement of the extension 34 and the brush carrier 17 on arcs will not cause binding. The 45 shafts 30 are connected by the arms 32 to the links 36 which are moved by the mechanism in the case 20 when the operating member 23 is reciprocated.

50 The operating member 23 is attached by two links 40 and 41 to the vertical shaft 42. 43 indicates a spiral spring connected at its upper end to an extension 40a on the arm 40 and at its lower end to the member 23. Through a parallelogram action the spring 43 serves to partially

counterbalance the weight of the member 23 so that it will bear very lightly against the surface of the material being cleaned. This construction also will permit member 23 to adjust itself to different heights provided or different thicknesses of material without bearing too heavily against the material. The frictional contact, however, with the material being cleaned is sufficient to reciprocate the member 23 as the cleaner is moved back and forth in order to oscillate 10

The shaft 42 at its upper end carries the arm 44 connected by the link 45 to the arm 46 pivoted on the shaft 47. The arm 46 carries the dog 147 adapted to engage the teeth 48 on the wheel 49 so that reciprocations of the dog will rotate the wheel 49 in a counter-clockwise direction as viewed in Fig. 6. Each complete reciprocation of the dog 147 will advance the wheel one tooth. Reverse rotation of the wheel 49 is prevented by the dog 50 pressed upwardly by the spring 51. The wheel 49 carries an eccentric 52 embraced by the eccentric strap 53 on the arm 54 which carries the dog 55 engaging the teeth 56 on the wheel 57. It will be seen that each rotation of the wheel 49 will advance the wheel 57 one tooth. Likewise, the wheel 57 contains a similar eccentric operating through similar mechanism so that each complete rotation of the wheel 57 will rotate the wheel 58 one tooth and likewise this wheel drives the wheel 59. The wheels 59, 57 are mounted on the shaft 160. The wheel 59 carries a pinion 161 operating the gear segment 162 on the arm 163 which is pivoted on the shaft 47 and is provided with a cross member carrying the pins 60 and 61 to which the inner ends of the links 36 are connected.

With the brush in its uppermost position the pins 60 and 61 are substantially one above the other. As the member 163 is slowly rocked the pins 60 and 61 are moved toward a horizontal position to extend the links 36, 36 to lower the brush holders. It will be seen that the feed mechanism is very slow. For example, the total brush feed may be only approximately $\frac{1}{4}$ inch and the feed mechanism may be so constructed that approximately 500,000 complete reciprocations of the member 23 are required to feed the brush downwardly $\frac{1}{4}$ of an inch. In so adjusting the mechanism it may be roughly estimated in ordinary operation the cleaner is given about 20 complete forward and backward movements per minute. At this rate, the brush would be fed

downwardly about $\frac{1}{4}$ of an inch for every 400 hours of use. It may be roughly estimated accordingly that this much use will ordinarily wear the bristles about $\frac{1}{4}$ of an inch.

If a new brush is installed the feed mechanism may be easily and quickly reset by means of the member 70. Pressing this member upwardly operates cam 71 to release the wheel 59. The cam 71 engages the pin 81 on the dog 72 and releases it from the wheel 59. Cam 73 also engages pin 82 on dog 80 and releases it from the wheel 59. Wheel 59 when thus released is free to rotate reversely to be reset. The tension of the belt 14 on the brush will then pull the brush up to starting position and again retract the links 36, 36.

While there are shown and described certain embodiments of the invention, it is to be understood that it is capable of many modifications. Changes, therefore, in the construction and arrangement may be made without departing from the spirit and scope of the invention as disclosed in the appended claims, in which it is intended to claim all novelty inherent in the invention as broadly as permissible, in view of the prior art.

What I claim as new, and desire to secure by Letters Patent is:

1. A suction cleaner, including: a nozzle; a brush associated with the nozzle and downwardly movable only with respect to the same; and means actuated by reciprocations of the cleaner in use for cleaning, for progressively and positively feeding said brush downwardly with respect to said nozzle a predetermined increment for each reciprocation.

2. A suction cleaner, including: a nozzle; a brush associated with the nozzle and downwardly movable only with respect to the same; and means actuated by reciprocations of the cleaner in use for cleaning, for progressively and positively feeding said brush downwardly with respect to said nozzle a predetermined and extremely small increment for each reciprocation.

3. A suction cleaner, including: a nozzle; a brush associated with the nozzle and downwardly movable only with respect to the same; and means actuated by reciprocations of the cleaner in use for cleaning, for progressively and positively feeding said brush downwardly with respect to said nozzle an increment of substantially five ten-millionths of an inch for each reciprocation.

CHARLES H. SPARKLIN.
